UNITED STATES PATENT OFFICE.

JOSEPH B. KISLINGER, OF NEW YORK, N. Y., ASSIGNOR TO MARIE B. KISLINGER, OF NEW YORK, N. Y.

DESIGN FOR A LOCKET.

Application filed January 30, 1926. Serial No. 16,338. Term of patent 14 years.

To all whom it may concern:

Be it known that I, JOSEPH B. KISLINGER, a citizen of the United States, residing in New York city, county and State of New York, have invented a new, original, and ornamental Design for Lockets, of which the following is a specification, reference being had to the accompanying drawing, forming a part thereof.

Fig. 1 is a front view of a locket embodying my new, original and ornamental design.

Fig. 2 is a rear view of the same.

Fig. 3 is an edge view of the same.

I claim:

The ornamental design for a locket substantially as shown.

JOSEPH B. KISLINGER.
